JAMES VARLEY, OF HUDSON CITY, NEW JERSEY.

Letters Patent No. 88,239, dated March 23, 1869; antedated March 15, 1869.

IMPROVEMENT IN NECK-TIE RETAINERS.

The Schedule referred to in these Letters Patent and making part of the same.

To all whom it may concern:

Be it known that I, JAMES VARLEY, of Hudson City, in the county of Hudson, and State of New Jersey, have invented a new, and useful Neck-Tie Retainer, of which the following is a full, clear, and exact description, reference being had to the accompanying drawing, forming part of this specification, and in which—

Figure 1 represents a front view of a retainer, constructed in accordance with my invention;

Figure 2, a back view of the same; and

Figure 3, a transverse section.

Figures 4, 5, and 6 are similar views of a modified form or construction of the retainer.

Similar letters of reference indicate corresponding parts.

This, my invention, relates to a spring-collar brooch, designed as a substitute for, or retainer of a neck-tie, or other like article of wear, the use or more prominent object of which is to conceal the button or stud to which the collar is fastened in front, also ends of the collar there meeting, and to form an ornament at such point, or place.

My invention consists in a shield or other fancifully-shaped plate, having any desired emblem or ornament upon it, or it may be plain, or, instead of a plate, an ordinary brooch or brooch-face piece, such portion, or device carrying, or having united to it, at its back, a spring, or yielding neck-clip, slotted to receive the shank of the button or stud-stitching, which unites the button to the garment, for action in concert with a catch, or projection on the rear face of the shield, or its equivalent, arranged to hold or lap over the edge of the button after the same has been entered by said slot receiving its shank between the shield and clip.

In thus speaking of a spring, or yielding neck-clip, it should be understood that the same may either be fixedly united to the brooch-face piece, or shield, as to possess the necessary elasticity in itself to permit of its receiving the button between said clip and catch, and after the catch has passed the button, to spring to and close over the latter, or the clip may be hinged to the shield, and be acted upon by an independent spring to thus operate.

When this spring-collar, or neck-tie retainer is made wholly of metal it may be got up cheap, and the shield or plate in front be ornamented with the insignia of any particular order, or society, the same, too, being more durable than a neck-tie or other like article of dress.

Having thus specified at large the character and peculiarity of my invention, the following continuous description, with reference to the accompanying drawing, will suffice to explain how the same is or may be carried out and applied.

Thus, referring, in the first instance, to figs. 1, 2, and 3, of the drawing—

A is the shield, or brooch-face piece, and

B, the spring, or yielding neck-clip, formed of curved side arms *a a*, body part *b*, slotted as at *c*, and united, by an upwardly-extending elastic arm or leg, *d*, to the back of the shield, near its top, as at *e*, where there is a fixed catch, or toothed projection, *f*, arranged in line with the slot *c*. This mode of attachment and construction of the clip gives an elastic character to the latter, which allows of the button being received between it and the catch, and of the brooch being slid upward, so as to pass the catch above the button, the slot *c* in the clip receiving the shank of the button, or that which is equivalent thereto, and after the brooch has been thus adjusted, the yielding neck-clip allowed to spring back, or close toward the shield, or latter toward the clip, to shoot the catch, or projection *f* over the button, and so, in connection with the slotted portion embracing the shank of the button, to securely hold it from falling, or slipping off the button.

In figs. 4, 5, and 6 of the drawing, the neck-clip B, similarly formed of side arms *a a*, and body-part *b*, with slot *c* in it, is hinged, as at *g*, to the shield A, and closed against or toward the latter by an independent spring, *h*, for operation in connection with the catch or projection *f*, as in the former case, the independent spring *h* taking the place of the elastic arm or leg *d*.

What is here claimed, and desired to be secured by Letters Patent, is—

1. A neck-tie retainer, formed of a shield or brooch-face piece A, and yielding neck-clip B, composed of curved arms *a a*, and body *b*, having a slot, *c*, in it, in combination with a catch, or projection, *f*, in rear of the shield or brooch-face piece, for operation together, substantially as specified.

2. The slotted neck-clip B, formed with an elastic extension, or arm, *d*, for attachment to the shield, or brooch-face piece A, and for action in concert with the catch, or projection *f*, constructed and arranged substantially as herein set forth.

JAMES VARLEY.
